UNITED STATES PATENT OFFICE

2,435,642

HEEL SANDER

Donald Bates, Baker, Oreg.

Application November 22, 1946, Serial No. 711,749.

2 Claims. (Cl. 51—238)

1

This invention relates to a machine for finishing the heels of shoes and it consists in constructions, arrangements and combinations herein described and claimed.

The heels of shoes often require sanding or leveling before leather lifts or rubber heels can be applied, and this in the past has been accomplished manually with no certainty that each heel of a pair of shoes will have the right angular relation with respect to the sole of the shoes.

It is therefore an important object of the invention to provide a machine in which a support is employed adjustable with respect to a grinding or sanding disk, the adjusting means including a locking means for maintaining an adjusted position, thereby insuring a like sanding or grinding of each shoe of a pair.

It is also an object of the invention to provide a novel and simple gauge means including a slideable spring-urged plate, the outer free end having a shoe support enabling proper alignment between the heel and the sole of a shoe and further including locking means for securing the plate in an adjusted position.

Additional objects, advantages and features of invention will be apparent from the following description and accompanying drawings, wherein

Figure 1 is a side elevation of the machine with a shoe in position for grinding or sanding.

Figure 2 is an end elevation thereof.

Figure 3 is a top plan view of the bed of the machine.

Figure 4 is a side elevation thereof.

Figure 5 is an end elevation thereof.

Figure 6 is a top plan view of the gauge and shoe support device detached.

Figure 7 is a side view thereof.

Figure 8 is an end view of the support.

Figure 9 illustrates a plan and edge view respectively, of a closure plate for securing the gauge and support within the bed of the machine.

Figure 10 is a top plan view of the locking means for securing the gauge and support in adjusted positions.

Figure 11 is a top plan view thereof.

There is illustrated a sanding or grinding machine 10 consisting of a casting substantially of rectangular shape in plan, having a planiform bed base 11 from which there are extended right angular end walls 12 and 13.

As may be seen in Figures 3 and 5 of the drawings, the bed 11 is formed with a pair of guideways 14 and 15, extending longitudinally of the bed the full length thereof and being positioned medially of the bed. The guide-way 14 is formed

at a level lower than the guide-way 15 and receives therein plates 16 and 17 constituting the combined gauge and support, as will now be described. A threaded opening 18 is formed in the base of the guide-way 14, inwardly of the end wall 13 adapted to register with an elongated slot 19 formed in the plate 16. The slot 19 is countersunk to accommodate the head 20 of a bolt 21 for securing the plate in position within the slot. By loosening the bolt 21 it will be apparent that the plate may be moved longitudinally of the slot for purposes of adjustment.

The plate 16 is formed with a tongue 22 of a width less than that of the plate proper defining respective shoulders 23. The plate 17 is bifurcated, forming a slot 24 of a width to slidably engage the tongue 22, the legs 25 thus formed being aligned with respective shoulders 23 and between each of the opposed shoulders and the ends of the legs a helical spring 26 is interposed. The springs 26 function to project the plate 17 beyond the outer edge of the slot 14 and the end plate 12, as shown in Figure 1.

A heel rest 27 is secured upon the outer end of the plate 17, in the present instance the rest being shown as a yoke member 28 bolted or otherwise secured to the plate and extending upwardly at right angles thereto. The arms 29 of the yoke mounts a rod 30 upon which a heel may be rested for sanding or grinding, as will be described hereinafter.

With the plates 16 and 17 assembled and disposed within the guide-way 14, a closure plate 31 is positioned in the guide-way 15 and secured by means of machine screws 32 adapted to engage threaded openings 33 in the guide-way 15.

It will be necessary to provide a lock means for securing adjustment of the plate 17, and as here shown, a threaded aperture 34 is provided in the guide-way 14 into which a screw 35 is engaged the screw 35 including a head 36 oscillatable by means of a handle 37 of a length so as to extend beyond the edge of the casting for ready manipulation. The screw 35 is adapted to impinge upon the lower side of the plate when the head is rotated in one direction, but readily retracted when rotated in the opposite direction for release of the plate.

The casting is provided with suitably spaced openings 38 for rigid mounting of a motor 39, the latter being centrally located so as to present the grinding or sanding disk 40 in alignment with the end plate 12.

In use, with the locking device in released position, the plate 17 together with the rest 27 will

be in its outermost projected position, a shoe is brought to rest upon the rod 30 and a rearward movement is imparted upon the shoe in the direction of the disk 40, until the sole of the shoe contacts the end wall 12 and the heel rests against the disk. The handle 37 is grasped and rotated so as to turn the screw 35 into impingement upon the plate 17 and the adjustment is secured. The motor 39 is now started to surface the heel and when this is accomplished the other shoe is similarly treated with assurance that both heels will be of the same height and of like bevel.

It will be apparent that the rest 27 can be quickly adjusted to another pair of shoes by merely actuating the handle 37 to release the plate 17 which will be urged outwardly by reason of the springs 26 and the adjustment of the shoes with respect to the disk 40 and the end plate 12 repeated.

While I have shown and described a preferred form of the device, this is by way of illustration only, and I consider as my own all such modifications in construction as fairly fall within the scope of the appended claims.

I claim:

1. A heel surfacing device comprising a base, said base having a pair of guide-ways arranged in superposed relation, the lower guide way being of narrower width, a plate adjustably fixed in said last named guide way, said plate having a forwardly extended tongue, a second plate in said guideway in advance of the first plate and having an open ended slot for receiving said tongue

therein, spring means between adjacent ends of said plates urging said named plate outwardly of said guide way, means for locking said second named plate in an adjusted position, against the tension of said spring means, a driven grinding disk mounted upon said base, the latter including respective end walls one of which is in vertical alignment with the outer face of the grinding disk, and a heel support carried on the outer end 10 of the second named plate adapted to position a heel of a shoe against the grinding disk and the ball portion of the sole of a shoe against the adjacent end wall of the base.

2. The structure of claim 1 in which the locking means comprises a stud threaded through the lower wall of the lower guide way for impinging the second named plate and a lever connected to said stud for rotating the same.

DONALD BATES.
